CHILD SAFETY SEAT FOR USE IN VEHICLES

Daniel A. Armstrong, Utica, and Thomas B. Bartholomew,
Orchard Lake, Mich., assignors to American Safety
Equipment Corporation, Encino, Calif.

Filed Oct. 1, 1973, Ser. No. 402,333

Term of patent 14 years

Int. Cl. D6—01

U.S. Cl. D6—7

FIG. 2.

FIG. 1.

FIG. 4.

FIG. 3.

FIG. 5.

FIG. 1 is a side elevational view of a child safety seat for use in vehicles showing our new design;

FIG. 2 is a front view;

FIG. 3 is a rear view;

FIG. 4 is a top view; and

FIG. 5 is a bottom view thereof.

We claim:

The ornamental design for a child safety seat for use in vehicles, as shown.
